UNITED STATES PATENT OFFICE

106,058

DESIGN FOR A BELT OR SIMILAR ARTICLE

Herman Pomerantz, New York, N. Y.

Application June 26, 1937, Serial No. 70,075

Term of patent 3½ years

To all whom it may concern:

Be it known that I, Herman Pomerantz, a citizen of the United States of America, residing in city of New York, county of New York, and State of New York, have invented a new, original, and ornamental Design for Belt or Similar Article, of which the following is a specification, reference being had to the accompanying drawing, forming part thereof.

I claim:

The ornamental design for a belt or similar article substantially as shown.

HERMAN POMERANTZ.
